UNITED STATES PATENT OFFICE

1,991,302

AUTOMATIC FIREARM WITH A MOVABLE BARREL

Rudolf von Frommer, Budapest, Hungary

Application March 19, 1932, Serial No. 599,957
In Hungary March 21, 1931

1 Claim. (Cl. 42—4)

In my Patent No. 1,574,770 of March 2, 1926 an operating handle for automatic fire arms actuated also manually is described, which is swingably connected to the breech bolt and cooperates with a coupling member, which couples and uncouples the handle with a part of the fire arm and especially with the closing spring of the breech bolt, for the purpose that when opening the breech bolt by hand the operator is not compelled to stretch the closing spring.

In the use of fire arms with a movable barrel and fitted with such a handle some disadvantages occur. When the fire arm is actuated manually, the discharged cartridge case must be pulled out from the loading chamber of the barrel by opening the breech-block. Now when a cartridge case is jammed in the loading chamber of the barrel, on drawing back the breech bolt, the barrel is taken along with the latter without opening the breech-block. The present invention has for its object to avoid this inconvenience by fixing the barrel automatically when opening the breech-block manually by the said swingable handle, so that the breech-block is opened on the withdrawal of the breech bolt, which pulls the cartridge case out of the chamber.

In the accompanying drawing one form of the invention is shown by way of example.

Fig. 1 is a top plan view of one part of the fire arm the fixing device being disengaged.

Fig. 2 is a similar view with the engaged fixing device.

Fig. 3 is a cross section taken on line 3—3 of Fig. 1.

Fig. 4 is a cross section taken on line 4—4 of Fig. 2.

A two armed fixing lever 3 is arranged transversely of the axis of the barrel and can be swung around its pivot 4 and is controlled by a spring 5. The fixing lever 3 cooperates with a recess or rest 2 of the barrel 1, and carries on one arm a shoulder 7 and on the other one a projection 6.

The nose 11 of the coupling arm or hook 12, which is under the action of a spring 8 and pivotally mounted on the pivot 9, bears upon the shoulder 7 of the lever 3, said arm 12 being moved by the operating handle 10. When the breech is fully closed that is to say it occupies its normal position (see Fig. 1) the nose 11 presses under the action of the spring 8 the fixing lever 3 into its disengaged position (see Fig. 3), the spring 8 being considerably stronger than the spring 5. In this state the barrel is freely movable and when the fire arm functions automatically, the backward shifting of said barrel is unrestrained. But if the fire arm is operated manually and the operating handle 10 is caught by the operator in order to withdraw the breech bolt by means of the latter, the handle 10 is instantly swung back, whereby the coupling arm 12 will be swung around the pivot 9 against the action of the spring 8. Thereby the nose 11 is removed from the shoulder 7 of the fixing lever 3, so that the spring 5 presses positively the projection 6 of the fixing lever 3 into the recess 2 of the barrel (see Figs. 2 and 4) whereby the barrel is fixed. If the operating handle 10 at the closing of the breech is pushed forward again, the nose 11 again presses back the shoulder 7 of the fixing lever 3, whereby the barrel is released again and can be freely moved backwards.

I claim:

In an automatic fire arm, a movable barrel having a recess therein, a breech bolt, a handle swingably connected to the breech bolt, a coupling arm moved by the said handle, a fixing member for the barrel, a spring adapted to push the said fixing member into the recess of the barrel to fix the barrel, a spring adapted to push said coupling arm toward said fixing member in the closed position of the breech bolt to hold the fixing member disengaged from the recess of the barrel.
